Primary Examiner — T Chase Nelson*Assistant Examiner* — Jonathan J. Han(74) *Attorney, Agent, or Firm* — Banner & Witcoff, Ltd.**(57) CLAIM**

The ornamental design for a shoe, as shown and described.

DESCRIPTION

FIG. 1 is a bottom first side perspective view of a shoe showing my design;

FIG. 2 is a bottom plan view thereof;

FIG. 3 is a bottom second side perspective view thereof;

FIG. 4 is a rear view thereof;

FIG. 5 is a first side view thereof; and,

FIG. 6 is a second side view thereof.

The even-length broken lines are directed to environment, represent unclaimed subject matter, and form no part of the claimed design.
